DESIGN FOR A HEAD FOR TOY COUPLERS

John R. Lettenberger, Queens Village, N. Y., assignor to The Lionel Corporation, New York, N. Y., a corporation of New York

Application September 14, 1940, Serial No. 95,052

Term of patent 3½ years

To all whom it may concern:

Be it known that I, John R. Lettenberger, a citizen of the United States of America, and a resident of Queens Village, in the county of Queens and State of New York, have invented a new, original, and ornamental Design for a Head for Toy Couplers, of which the following is a specification, reference being had to the accompanying drawing, forming a part thereof.

In the drawing:

I claim:

The ornamental design for a head for toy couplers, as shown.

JOHN R. LETTENBERGER.
